W. R. BLAIR,
AWL FEED ADJUSTMENT FOR SHOE STITCHING MACHINES.
APPLICATION FILED MAY 24, 1913.

UNITED STATES PATENT OFFICE.

WILLIAM R. BLAIRE, OF ST. LOUIS, MISSOURI, ASSIGNOR TO LANDIS MACHINE COMPANY, OF ST. LOUIS, MISSOURI, A CORPORATION OF MISSOURI.

AWL-FEED ADJUSTMENT FOR SHOE-STITCHING MACHINES.

1,092,892.

Specification of Letters Patent. Patented Apr. 14, 1914.

Application filed May 24, 1913. Serial No. 769,703.

To all whom it may concern:

Be it known that I, WILLIAM R. BLAIRE, a citizen of the United States, residing at city of St. Louis, State of Missouri, have invented a certain new and useful Improvement in Awl-Feed Adjustments for Shoe-Stitching Machines, of which the following is a full, clear, and exact description, such as will enable others skilled in the art to which it appertains to make and use the same, reference being had to the accompanying drawings, forming part of this specification, in which—

Figure 1 is a top view of a portion of a shoe stitching machine illustrating my invention. Fig. 2 is a side view of the same. Fig. 3 is a detail in section on line A—A of Fig. 1. Fig. 4 is a section on line B—B of Fig. 1. Fig. 5 is a section on line C—C of Fig. 2.

My invention relates to sewing machines, and specifically to an improved form of adjustment for regulating the stroke of the feeding awl, and is designed as an improvement upon the device illustrated and described in patent to Pedersen, No. 811,582, of February 6, 1906.

The principal object of my invention is to provide an accurate and easily manipulated mechanism for adjusting the length of the stroke of the feeding awl in shoe stitching machines while the machine is in operation.

Another object of my invention is to provide a means for taking up wear and slight displacements in the awl shifting mechanism, and adjust the location of the zone of the awl's movement.

A further object of my invention is to provide a stitch adjusting mechanism by means of which the machine may be adjusted accurately for stitches of various predetermined lengths.

Further objects of my invention will be obvious or hereinafter pointed out.

In the use of shoe stitching machines wherein the work is fed forward by a shifting awl which engages the work and carries it forward, it is frequently desired to change the length of the stitch while the work is on the machine. If the machine is stopped while the stitch is being adjusted, there is an appreciable loss of time and the probability of irregularity in the sewing. Unless the operator is quite familiar with the particular machine, it is frequently necessary to

make experimental adjustment before the proper length of stitch is obtained. Furthermore, as the machine is used and becomes somewhat worn or portions sprung, the same extent of adjustment will not produce the same variation in the stitch.

From an inspection of the drawings, it will be understood that 1 is a portion of the frame of the machine, 2 a slotted cam, 4 the awl shifting lever which is oscillated horizontally by the engagement of a roller 5 carried on its rear end and constituting a bearing member operating in the slot of cam 2.

6 is a square rock shaft which is actuated through link 7 to give rotary movement to the collar 9 which is mounted to rotate therewith but slidably longitudinally thereon. Collar 9 carries the awl bar in which is mounted the awl 8. The rotary movement of collar 9 with shaft 6 gives the awl bar and awl an oscillatory movement. The forward end 4^a of the awl shifting lever 4 engages the collar 9, and upon the horizontal oscillation of lever 4 the awl will be shifted horizontally on rock shaft 6 to feed the work when it is engaged by the awl. Shifting lever 4 is provided with a slot 4^b which is disposed parallel with the longitudinal axis of lever 4. Lever 4 is provided with upper and lower bearing faces, the latter of which rests upon a proper bearing portion of frame 1, and the former of which provides a bearing for a shiftable plate 11. Depending from shiftable plate 11 is a fulcrum pin 12 which is provided with a bushing 14, contacting with the sides of slot 4^b, and forming a bearing for the pivotal movement of the awl shifting lever 4. Fulcrum pin 12 carries a bearing plate 15 which contacts with a bearing surface on the frame 1, holding lever 4 and shiftable plate 11 in contact upon frame 1. A pin 16 is mounted in frame 1 and operates in an arcuate slot 17 in lever 4. The purpose of this pin and slot engagement is to prevent longitudinal movement of lever 4, but the width of slot 17 is sufficient to accommodate the slight variations in arcuate movement relative to pin 16 due to variations in the oscillation of lever 4. Shifting plate 11 is provided on its upper surface with rack teeth which are engaged by a pinion 18 carried upon a shaft 19 mounted in bearings 20 and adjustable by means of the thumb screw 21. Upon the

100
105
110

desired rotation of pinion 18 by thumb screw 21, shiftable plate 11 will be shifted longitudinally of lever 4, thereby changing the fulcrum point of lever 4 on fulcrum pin 12, by the shifting of said pin in slot 4^b. This shifting of the fulcrum point of lever 4 necessarily varies the length of the stroke of the end 4^a of said lever, and consequently the length of stroke of awl 8. Thumb screw 21 is provided with a scale 24 by means of which the foregoing adjustment may be regulated, the scale being arranged to indicate the various lengths of stitches.

To effect the desired adjustment of the stitch, it is not necessary, by virtue of this improved adjusting mechanism, to stop the machine while the pivot is being adjusted. This is a highly desirable feature inasmuch as it is frequently desired to change the length of the stitch while the work is on the machine. Moreover, this adjusting means provides a very accurate adjustment, by which stitching of the desired length may be secured positively and without experimental adjustments.

As illustrated in Fig. 5, the outer bearing 20 is provided with a spring pressed pin 25 which is adapted to engage in any of a series of depressions 26 in the inner face of thumb screw 21, whereby the parts are properly centered and the adjusting members retained against displacement.

Upon continued use of the machines, it frequently occurs that the forward end 4^a of lever 4 and the collar 9 become worn at their points of bearing. This necessarily renders the movement inaccurate and the stitch irregular. Furthermore, the forward end 4^a of lever 4 frequently becomes sprung due to the resistance encountered by the lever in its operation of feeding the work. These displacements of parts would change the zone of the awl's movement and thus affect the accuracy of the adjustment of the stitch so that it would not correspond to the indications of the scale 24. In order to compensate for these inaccuracies, I provide the adjusting means illustrated in Fig. 4 whereby the displacement of parts may be taken up. As illustrated in section in said

last named figure, it will be seen that roller 5 is carried on an eccentric pin 27 pivotally mounted in link 4 and secured by a jam nut 28. When it is desired to take up any inaccuracies in lever 4, jam nut 28 may be loosened and eccentric pin 27 rotated so as to shift roller 5 laterally of lever 4, and thus give end 4^a the proper adjustment.

From the foregoing, it will be understood that my invention comprises a simple adjusting device by virtue of which the stitch of the machine may be adjusted while the machine is in operation, and stitches of a predetermined length may be positively and accurately secured. Furthermore, a means is provided whereby the parts may be adjusted to maintain the proper coördination between the adjusting scale and the work feeding mechanism.

I am aware that modifications may be made in the device shown, and I, therefore, intend that my invention as claimed be construed to cover all obvious modifications.

What I claim is:

1. In a machine of the class described, a work feeding awl, a shifting lever for the same, a fulcrum pin upon which said lever is pivoted, means for shifting said pin to vary the extent of operation of said lever, a scale adapted to indicate the extent of operation of said lever, means for oscillating said lever, and means for adjusting the working position of said lever circumferentially relative to said fulcrum pin for the purpose described.

2. In a machine of the class described, a work feeding awl, a shifting lever for the same, a cam for operating the shifting lever, a bearing member carried by said shifting lever and coöperating with said cam, and means whereby said shifting lever may be adjusted relative to said bearing member for the purpose described.

In testimony whereof I hereunto affix my signature in the presence of two witnesses, this 19th day of May, 1913.

WILLIAM R. BLAIR.
